US00D868360S

(12) **United States Design Patent** (10) Patent No.: **US D868,360 S**
(45) Date of Patent: ** *Nov. 26, 2019

(54) **ELECTRONIC CIGARETTE**

(71) Applicant: **Altria Client Services LLC**,
Richmond, VA (US)

(72) Inventor: **Mitchell Stone**, Staffordshire (GB)

(73) Assignee: **Altria Client Services LLC**,
Richmond, VA (US)

(*) Notice: This patent is subject to a terminal disclaimer.

(**) Term: **15 Years**

(21) Appl. No.: **29/662,843**

(22) Filed: **Sep. 10, 2018**

Related U.S. Application Data

(62) Division of application No. 29/592,199, filed on Jan. 27, 2017, now Pat. No. Des. 830,625.

(57) **CLAIM**

The ornamental design for an electronic cigarette, as shown and described.

DESCRIPTION

FIG. 1 is a perspective view of an electronic cigarette; FIG. 2 is a front view of the electronic cigarette; FIG. 3 is a rear view of the electronic cigarette; FIG. 4 is a left side view of the electronic cigarette; FIG. 5 is a right side view of the electronic cigarette; FIG. 6 is a top view of the electronic cigarette; and, FIG. 7 is a bottom view of the electronic cigarette. The dashed broken lines in the drawings represent environmental subject matter that forms no part of the claimed design.
